UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

FLASH WATER COOLER.

Application filed February 15, 1926. Serial No. 88,342.

This invention relates to refrigerators. It is the purpose of the invention to provide a water cooler in connection with a power refrigerator or any form of domestic 5 refrigeration other than ice. Inasmuch as the temperature in the so-called brine chamber is usually kept down somewhere around zero, it is impossible to have a water container or a water coil therein for storing 10 water for drinking purposes, as it will obviously freeze and become inoperative. I have devised a simple solution of this problem by utilizing the extreme cold of the brine chamber for cooling the water by controlling my system in a way where the contact of the water with the brine chamber can only be transitory. This achieves the 15 cooling in a very effective simple way.

In the drawings:

20 Fig. 1 is a front elevation of an electrical refrigerator embodying my new invention.

Fig. 2 is a similar view showing a slight modification of the invention. In both 25 these views the door of the refrigerator has been omitted for the purpose of clearness.

Referring to Fig. 1, the outline of the cabinet or refrigerating case will be clear. Within the upper left hand chamber is provided a so-called brine tank, which is ordinarily however, a solution of alcohol and water. Water is taken up through the service line to the back of the refrigerator and then passes down through the brine chamber 30 in the form of a coil *c*, in the brine tank. This coil is given several convolutions so as to bring it into intimate contact with the frigid brine. This arrangement has some similitude to the so-called 35 instantaneous gas water-heater, where the water is heated on the run. So here the heat exchange takes place on the run while the water is passing through this frigid zone.

40 However, in place of putting the water control valve at the spigot of the cock *d*, as is the ordinary custom, I have provided it at the point *e*. Here the valve is located in a region where the temperature ordi-

narily does not reach the freezing point and 50 consequently the water backed up in the pipe is not frozen so as to impair its operation. No valve is placed on the spigot *d*, consequently the spigot is bound to drain 55 itself and all the pipe located in the frigid zone. In order to insure that the cooling coil will drain, the coil may be made of pipe of sufficient size to prevent capillarity. Preferably, a drain *f* is located immediately 60 below the spigot *d* to take off any excess water which is not taken in the container inserted below the spigot.

In Fig. 2 a slight modification is shown. Here the water supply is in the form of an inverted bottle *g*, and the coil *h* does not 65 run directly through the brine chamber but in such close proximity to it as to achieve the same result.

What I claim is:

1. In a refrigerator, the combination of 70 a cabinet, means for abstracting heat to bring a portion of the interior of said cabinet below the freezing point, and means for transferring running water through such frigid zone to cause flash heat exchange as 75 regards the running water, said means permitting the water to drain whereby water is not maintained in such frigid zone.

2. In a refrigerator, the combination of 80 a cabinet, means for giving a portion of the cabinet a freezing temperature, a coil for running drinking water through such frigid zone, and a valve for controlling the water located in the pipe at a point in the rear of where the water enters the frigid 85 zone.

3. In a refrigerator, the combination of 90 a cabinet, means for establishing a freezing zone in a portion of the cabinet, a pipe for running water for drinking purposes running through said frigid zone and terminating in an open spigot, and means in the rear of a point where the pipe enters the frigid zone for controlling the running of water through said pipe.

4. The combination with a refrigerator having a cooling medium, means to maintain the temperature of the medium below

the freezing point of water, of a pipe running through the medium for conducting drinking water, a valve for controlling the flow of the water which is positioned outside of the medium and to the rear of the point where the pipe enters the medium, and a cock for the discharge of water after

the same was passed through the cooling medium, the said cock permitting the water which is in the pipe forward of the said valve to drain out when the valve is closed.

In testimony whereof I have affixed my signature.

LLOYD G. COPEMAN.
